UNITED STATES PATENT OFFICE.

JOHN W. SKILTON, OF DAYTONA, FLORIDA.

HINGE.

SPECIFICATION forming part of Letters Patent No. 757,784, dated April 19, 1904.

Application filed August 11, 1903. Serial No. 169,123. (No model.)

To all whom it may concern:

Be it known that I, JOHN W. SKILTON, a citizen of the United States, residing at Daytona, in the county of Volusia, State of Florida, have 5 invented certain new and useful Improvements in Lubricating Ball-Bearing Hinges, of which the following is a specification, reference being had therein to the accompanying drawings.

This invention relates to a lubricating ball-bearing hinge, and particularly to a structure embodying a pintle and socket carried by opposite leaves of the hinge.

The invention has for an object to provide one member of the hinge with a socket adapted 15 to contain a ball or roller bearing upon which the pintle from the opposite member will rest and to form this socket so as to provide a chamber for containing lubricant, whereby a perfect ease of movement in the operation of 20 the hinge is obtained, and the pintle being submerged in the lubricant is thoroughly lubricated and protected against rust where the hinge is used in an exposed position.

Other and further objects and advantages 25 of the invention will be hereinafter set forth and the novel features thereof defined by the appended claims.

In the drawings, Figure 1 is an elevation of the hinge with the socket member in section. 30 Fig. 2 is a vertical section on the line 2 2 of Fig. 1, and Fig. 3 is a plan of the socket member of the hinge.

Like letters of reference refer to like parts in the several figures of the drawings.

The letter A designates a leaf or securing- 35 plate comprising one member of the hinge, and B a similar plate of the opposite member, which plates may be of any desired construction or configuration. The leaf A is provided 40 with a socket A', which is closed at its lower end A² and there provided with a curved bottom A³, upon which a bearing-ball A⁴ is disposed. This socket, closed at its lower end, forms an oil cup or chamber to receive the 45 lubricant, and for facilitating the introduction and retaining sufficient oil to thoroughly

fill the socket the upper portion thereof is recessed or enlarged, as shown at A⁵. The opposite member of the hinge is provided with a pintle B' depending therefrom and 50 adapted to enter the socket hereinbefore described, while the lower end of this pintle is curved or suitably shaped, as shown at B², to secure the minimum of frictional contact with the ball or bearing surface at the lower end 55 of the socket.

It will be seen that when the parts are assembled the pintle is provided with a ball-bearing at its lower end, upon which the weight of the member carried by the leaf 60 thereof is sustained while this contact and bearing is thoroughly lubricated by means of the oil-cup formed in the socket, thus securing a hinge embodying the greatest ease of 65 movement, as the friction is reduced to the minimum while the bearing members of the hinge are protected by the oil-cup against rust or the entrance of grit by the body of oil which is retained at the upper recessed portion of the cup.

It will be obvious that changes may be made in the details of construction and configuration without departing from the spirit of the invention as defined by the appended 70 claims.

Having defined my invention and set forth its merits, what I claim, and desire to secure by Letters Patent, is—

1. In a hinge, a leaf having at one side a socket member closed at its lower end and provided with an integral bearing-face, a single bearing-ball disposed at the base of said socket and resting upon said face, a pintle member carried by one edge of a co-operating leaf and located within said socket and provided with 80 a contact-point at its lower end bearing upon said ball, and an upper portion for said socket spaced from the base of the pintle.

2. In a hinge, a leaf having at one edge a socket member closed at its lower end and provided with a concave face, a single bearing-ball disposed at the base of said socket, a 90

pintle member carried by one edge of a co-operating leaf and located within said socket and provided with a convex contact-point at its lower end bearing upon said ball, and an upper recessed portion for said socket spaced from the base of the pintle and adapted to receive and retain a body of lubricant.

In testimony whereof I affix my signature in presence of two witnesses.

J. W. SKILTON.
